WINDOW SASH MOUNTING AND OPERATING
MECHANISM

Robert E. Bemis, Houston, Tex.

Application July 25, 1945, Serial No. 606,985

8 Claims. (Cl. 268—108)

1

This invention relates to a window sash mounting and operating mechanism.

An object of the invention is to provide novel means for mounting a window sash whereby the sash may be conveniently opened and closed.

Another object of the invention is to provide means for mounting a window sash, or similar closure, whereby the sash, or closure, may be moved to open position to allow adequate circulation of air but to exclude the rain.

It is a further object of the invention to provide a window sash mounting of the character described whereby the sash, when moved to closed position will form an effective seal with the window casing so as to exclude rain and moisture.

It is another object of the invention to provide a sash mounting that may be easily operated.

A still further object of the invention is to provide in combination with said sash and mounting a window blind by means of which the admission of light and air may be controlled.

With the above and other objects in view the invention has particular relation to certain novel features of construction, operation and arrangement of parts, an example of which is given in this specification and illustrated in the accompanying drawings, wherein:

Figure 1 is a vertical, sectional view taken on the line 1—1 of Figure 3 showing the sash in closed position.

Figure 2 is a similar view showing the sash open.

Figure 3 is a vertical, sectional view taken on the line 3—3 of Figure 4.

Figure 4 is a vertical, sectional view taken on the line 4—4 of Figure 3.

Figure 5 is a fragmentary, horizontal, sectional view taken on the line 5—5 of Figure 3.

Figure 6 is a fragmentary, horizontal, sectional view of the window blind employed; and

Figure 7 is a vertical, sectional view thereof taken on the line 7—7 of Figure 6.

Referring now more particularly to the drawings wherein like numerals of reference designate similar parts in each of the figures, the numeral 1 designates the window casing which, in general construction, is of conventional form. It may be composed of wood or of sheet metal, the latter construction being shown in Figure 5. At the top and bottom of the window casing there are the transverse outwardly and downwardly tapering seats 2 and 3.

The numeral 4 designates the sash, as a whole, which may be of any conventional construction

2

but whose upper and lower ends are downwardly and outwardly tapered so as to fit closely against the tapering seats 2 and 3 when the sash is closed, as shown in Figures 1 and 4.

5 The window casing is formed with the enclosed vertical side spaces 5 and 6 in which the mechanism mounting the sash is located.

The numeral 7 designates a transverse shaft which is mounted to rotate in suitable bearings 10 in the casing and which is located at the top of the casing.

10 Fixed on this shaft in the respective spaces 5 and 6 are the crossheads 8, 8. The upper ends of the links 9, 9 are pivoted to the corresponding ends of said crossheads and the lower ends of these links are pivoted to the lift levers 10, 10 which are located in the spaces 5 and 6 at the lower ends thereof. The outer ends of these lifting levers are pivoted to the window casing, as shown in Figures 1 and 2, and their inner ends are downwardly turned and are pivoted to the free ends of the downwardly and outwardly declining brackets 11, 11 which are fastened to the lower end of the sash frame on each side.

15 25 Fastened to the top of the window casing, one on each side, are the brackets 12, 12 and the triangular swinging plates 13, 13 are pivoted at corresponding inner apexes to the brackets 12, 12. The other ends of the crossheads 8 are connected to the upper outer apexes of said swinging plates by means of the links 14, 14.

20 30 Fastened on the sides of the sash frame are the brackets 15 and these brackets are connected to the lower apexes of the swinging plates 13 by means of the links 16, 16.

35 40 Fixed to the shaft 7 in the space 6 of the casing there is an arm 17 and pivotally connected, at its upper end, to the free end of this arm, there is a link 18. The lower end of this link is pivoted to the free end of one of the arms of the bell-crank 19 and the free end of the other arm of said bell-crank is pivoted to one end of the link 20. The other end of this link 20 is pivoted to a nut 21 which is threaded onto the outwardly threaded shaft 22. This shaft is mounted to rotate in outer and inner bearings in a casing 23 which is located in the space 6 and which is fastened to the adjacent side of the window casing. The bell-crank 19 is also mounted in this casing 23 and the link 20 and nut 21 are enclosed by it.

45 50 55 The inner end of the shaft 22 extends into a bore 24 in the side of the casing 1 and is polygonal in shape to receive a socket wrench 25 by

means of which the shaft 22 may be turned so as to move the nut 21 along said shaft.

As the shaft 22 is turned to move the nut 21 inwardly the bell-crank 19 will be actuated to cause a downward pull on the link 18 which, in turn, will pull the arm 17 downwardly and correspondingly rotate the shaft 7. The rotation of the shaft 7 will revolve the crossheads 8 with a lifting effect on the links 9, 9 so that the levers 10 will be moved upwardly. At the same time the links 14 and the swinging plates 13 will be actuated to move the lower apexes of said swinging plates upwardly and inwardly. The sash 4 will thus be lifted and its lower end will be moved slightly outwardly on account of the connection of the outer ends of the levers 10 with the brackets 11 but by reason of the connection of the links 16 with the brackets 15 the upper end of the sash will be moved further inwardly than the lower end thereof thus allowing circulation beneath and above the sash as well as about the sides thereof.

The sash mounting mechanism in the spaces 5 and 6 operate in unison being simultaneously operated by the common shaft 7.

Upon rotation of the shaft 22 in the other direction the nut 21 will be moved outwardly and the movement of the sash 4 will be reversed and the sash will be moved outwardly and downwardly and its upper and lower ends will be seated against the corresponding seats, or faces, 2 and 3 and the window opening thus tightly closed by the sash.

Mounted in the window casing 1 outside of the sash 4 there is a Venetian blind comprising the spaced, vertical side bars 26, 23 preferably angle-irons and the spaced cross slats 27. The ends 23 of these cross slats are overturned at right angles to the slats and have the end extensions which are pivoted to the bars 26. The overturned ends 28 of the upper and lower cross slats each have the pintles 29, 29 which are located in the U-shaped bearings 30, 30 which are fitted into upper and lower slots 31, 31 in the inner sides of the window casing, as more clearly shown in Figures 3 and 4. One of the overturned ends, as 28a, of one of the cross slats 27 has an outwardly turned tongue 32.

There is a shaft 33 which works through a suitable bearing in the casing 23, as shown in Figure 3, and whose inner end has a sleeve 34 welded thereon and provided with a transverse slot 35 to receive the tongue 32. This sleeve works through a bearing 36 in the window casing and its outer end has a crank 37 thereon within the casing 23. A link 38 has one end pivoted to the free end of the crank 37 and has its other end pivoted to a nut 39 which is threaded onto the outwardly threaded shaft 40 whose ends are mounted to rotate in bearings in the casing 23. The inner end of the shaft 40 is extended into a bore in the inner side of the window casing 1, and is polygonal in shape to receive the socket wrench 42 by means of which it may be turned. Upon turning the wrench 42 in one direction the shaft 40 will be correspondingly turned and will actuate the nut 39, which in turn will cause rotation of shaft 33 so as to close the Venetian blind and when turned in the other direction the blind will be operated into open position.

The drawings and description are illustrative merely while the broad principle of the invention will be defined by the appended claims.

What I claim is:

1. In combination with a window casing and

a sash therein; a transverse shaft rotatably mounted on the casing, lift levers pivoted at one end to the casing and pivoted at the other ends to the lower part of the sash, swinging elements pivoted at their upper ends relative to the casing, links connecting the lower ends of said elements to the sash, means connecting said levers and elements with the shaft, said levers being mounted to elevate the sash and swinging elements being mounted to the upper end of the sash to move it from the casing when the shaft is rotated in one direction and said levers and elements being mounted to lower the sash and move it into sealing relation with the casing when the shaft is rotated in the other direction.

2. In combination with a window casing and a sash therein; a transverse shaft rotatably mounted on the casing, lift levers pivoted at one end to the casing and pivoted at the other ends to the lower part of the sash, swinging elements pivoted at their upper ends relative to the casing, links connecting the lower ends of said elements to the sash, links connecting said levers and elements, respectively with the shaft, said levers and elements being mounted so that the levers will elevate the sash and swinging elements and links connected thereto will move the sash from the casing when the shaft is rotated in one direction and will lower the sash and move it into sealing relation with the casing when the shaft is rotated in the other direction, and means for rotating the shaft.

3. The combination with a window casing and a window sash therein; of a transverse shaft on the casing, cross heads on the shaft, lift levers pivoted at one end to the casing and whose other ends are pivoted to the sash, links connecting said levers to corresponding ends of the cross heads, swinging plates pivoted at their upper ends relative to the casing, links connecting the lower ends of the plates to the sash, links connecting the other ends of the cross heads to said plates, said cross heads being effective to swing said levers and plates about their pivots as the shaft is rotated back and forth, to move the sash away from, and in sealing relation with the casing.

4. The combination with a window casing and a window sash therein; of a transverse shaft on the casing, cross heads on the shaft, lift levers pivoted at one end to the casing and whose other ends are pivoted to the sash, links connecting said levers to corresponding ends of the cross heads, swinging plates pivoted at their upper ends relative to the casing, links connecting the lower ends of the plates to the sash, links connecting the other ends of the cross heads to said plates, said cross heads being effective to swing said levers and plates about their pivots as the shaft is rotated back and forth to move the sash away from, and in sealing relation with, the casing, and means for rocking the shaft.

5. The combination with a window casing and a window sash therein; of a transverse shaft on the casing, cross heads fixed on the shaft, lift levers pivoted at one end to the casing and whose other ends are pivoted to the lower portion of the sash, links connecting said levers to corresponding ends of the cross heads, swinging plates pivoted at their upper ends relative to the casing, links connecting the lower ends of the plates to the sash, links connecting the other ends of the cross heads to said plates, said cross heads being effective to swing said levers and plates about

their pivots as the shaft is rotated back and forth to move the sash away from, and in sealing relation with, the casing, means for rocking said shaft comprising an arm fixed thereto, a link connected to the arm and means for manually reciprocating the link longitudinally back and forth to rock the shaft.

6. In combination with a window casing and a sash therein; a transverse shaft rotatably mounted on the casing, lift levers pivoted at one end to the casing and pivoted at the other ends of the lower part of the sash, swinging elements pivoted at their upper ends relative to the casing, links connecting the lower end of said elements to the sash, means connecting said levers and elements with the shaft, said levers being mounted to elevate the sash and said elements and the links connected therewith being arranged to move the sash from the casing when the shaft is rotated in one direction and to lower the sash and move it into sealing relation with the casing when the shaft is rotated in the other direction, means for rocking said shaft comprising a link connected thereto, means for reciprocating the link longitudinally back and forth to rock the shaft, said reciprocating means including a threaded shaft, a nut threaded thereon, means connecting the nut to the reciprocable link and arranged to reciprocate the link as the nut is moved along its shaft and means for rotating the threaded shaft to move said nut along its shaft.

7. In combination with a window casing and a sash therein; a transverse shaft rotatably mounted on the casing, a pair of brackets secured to the lower end of the sash and extending within the casing, a pair of lift levers pivoted, at one end, to the sides of the casing and pivoted, at their other ends, to the brackets, swinging elements pivoted, at their upper ends, relative to the casing to swing at right angles to the sash, links connecting the lower ends of said elements to the sash, cross heads fixed to the shaft, links connecting said lift levers to corresponding ends of the cross heads, links connecting the other ends of the cross heads to said swinging elements whereby upon rotation of the shaft in one direction the sash will be lifted by the lift levers and swung away from the casing by the swinging elements and the links connecting said elements with the sash.

8. In combination with a window casing and a sash therein; a transverse shaft rotatably mounted on the casing, a pair of brackets secured to the lower end of the sash and extending within the casing, a pair of lift levers pivoted, at one end, to the sides of the casing and pivoted, at their other ends, to the brackets, swinging elements pivoted, at their upper ends, relative to the casing to swing at right angles to the sash, links connecting the lower ends of said elements to the sash, cross heads fixed to the shaft, links connecting said lift levers to corresponding ends of the cross heads, links connecting the other ends of the cross heads to said swinging elements whereby upon rotation of the shaft in one direction the sash will be lifted by the lift levers and swung away from the casing by the swinging elements and the links connecting said elements with the sash, an outwardly threaded shaft mounted in the casing, a bell-crank mounted in the casing, a nut threaded onto said outwardly threaded shaft, a link connecting said nut with one arm of the bell-crank, an arm fixed to said other shaft and a link connecting the free end of the arm to the other end of the bell-crank whereby upon rotation of the threaded shaft said other shaft will be correspondingly rotated.
